UNITED STATES PATENT OFFICE

161,578

COMBINED WALL DESK AND MAGAZINE RACK

Eli A. Farnham, Edgerton, Ohio

Application November 21, 1949, Serial No. 6,174

Term of patent 7 years

(Cl. D33—7)

To all whom it may concern:

Be it known that I, Eli A. Farnham, a citizen of the United States of America, residing at Edgerton, Williams County, Ohio, have invented a new, original, and ornamental Design for Combined Wall Desk and Magazine Rack, of which the following is a specification, reference being had to the accompanying drawings, forming a part hereof.

Fig. 1 is a perspective view of the combined wall desk and magazine rack;

Fig. 2 is an end elevation, with the desk open; and

Fig. 3 is a front view of the open desk of Fig. 2.

I claim:

The ornamental design for a combined wall desk and magazine rack, as shown.

ELI A. FARNHAM.
